FLUID VENDING MACHINE

Sam B. Norris, Jr., 1056 Humble Road, El Paso, Tex.

Filed July 22, 1963, Ser. No. 75,892

Term of patent 14 years

(Cl. D52—3)

FIG. 1.

FIG. 2.

FIG. 3.

FIG. 1 is a top plan view of a fluid vending machine embodying my new design;

FIG. 2 is a front elevational view thereof, the rear being essentially the same as the front shown except for a small access door not shown in place of the coin boxes disclosed on the front of the machine; and

FIG. 3 is a right side elevational view thereof, the left side being a mirror image of the side shown.

The dominant feature of my design resides in the portion as shown in full lines.

I claim:

The ornamental design for a fluid vending machine, as shown and described.
